UNITED STATES PATENT OFFICE.

RUSSELL WHITCOMB, OF ELIZABETH, NEW JERSEY.

SUSPENDING DEVICE.

1,112,581.

Specification of Letters Patent.

Patented Oct. 6, 1914.

Application filed September 9, 1913. Serial No. 788,834.

To all whom it may concern:

Be it known that I, RUSSELL WHITCOMB, a citizen of the United States, residing at Elizabeth, in the county of Union and State 5 of New Jersey, have invented certain new and useful Improvements in Suspending Devices; and I do hereby declare the following to be a full, clear, and exact description of the invention, such as will enable others 10 skilled in the art to which it appertains to make and use the same, reference being had to the accompanying drawings, and to characters of reference marked thereon, which form a part of this specification.

15 The present invention relates, generally, to improvements in devices for hanging curtains, draperies and other materials; and the invention has reference, more particularly, to a novel construction of hanger or 20 supporting device which provides strong gripping characteristics and which eliminates danger of tearing the fabric supported thereby or accidental displacement or removal of the hanger or supporting device from the 25 fabric with which it is connected.

The present invention has for its principal 30 object to provide a simple, strong, durable, slightly and easily attached hanger or supporting device for curtains, draperies and the like, the same being of a novel construction which offers highly efficient gripping or holding characteristics, while also providing a pleasing and slightly ornamental effect.

The present invention has for a further 35 object to provide a novel hanger or supporting device of the character above described which readily lends itself to a varied treatment for securing a wide scope of ornamental effects without disturbing or interfering 40 with its mechanical efficiency in supporting fabrics of all kinds from the lightest weight sheer fabrics to the heaviest of curtains and portières.

Another object of the present invention 45 is to provide a hanger or supporting device which can be used with the well-known curtain-rod provided with traveling rings, or which may be connected directly with the curtain-rod itself so as to obviate additional 50 traveling rings, as may be desired by or suit the convenience of the user.

Other objects of the present invention not

at this time more particularly enumerated will be clearly understood from the following detailed description of the present invention. 55

The invention consists, primarily, in the novel construction of hanger or supporting device hereinafter more fully set forth; and, furthermore, this invention consists in the 60 various arrangements and combinations of the several devices and parts, as well as in the details of the construction of the same, all of which will be more fully described in detail in the following specification and then 65 finally embodied in the clauses of the claim which are appended to and which form an essential part of the said specification.

The invention is clearly illustrated in the accompanying drawings, in which:— 70

Figure 1 is a front face view of the novel hanger or supporting device made according to and embodying the principles of the present invention, the same being shown in its connected and supporting relation with a 75 curtain or drapery. Fig. 2 is a rear or back face view of the same. Fig. 3 is a horizontal cross section of the same taken on line 3—3 in said Fig. 1, said view being drawn on an enlarged scale. Fig. 4 is a vertical 80 cross section of the same taken on line 4—4 in said Fig. 1, said view being also drawn on an enlarged scale. Fig. 5 is a plan view of a blank from which said novel hanger or supporting device is formed. Fig. 6 is a 85 plan view of a slightly modified form of blank from which said novel hanger or supporting device is formed. Fig. 7 is a plan view of another modified form of blank from which the said novel hanger or supporting 90 device may be formed. Fig. 8 is a vertical cross section of said hanger or supporting device similar to that shown in Fig. 4, but illustrating a modified arrangement of the supporting element of the hanger or supporting 95 device. Fig. 9 is a front face view of a slightly modified construction of hanger or supporting device still embodying, however, the general principles of the present invention. Fig. 10 is a rear face view of the 100 same. Fig. 11 is a horizontal cross section of the same, taken on line 11—11 in said Fig. 9, said view being drawn on an enlarged scale. Fig. 12 is a vertical cross section of

the same, taken on line 12—12 in said Fig. 9, said view being also drawn on an enlarged scale. Fig. 13 is a horizontal cross section, similar to that shown in Fig. 11, but illustrating still another slightly modified construction of the novel hanger or supporting device.

Similar characters of reference are employed in all of the hereinabove described views to indicate corresponding parts.

Referring now to the said drawings the reference character 1 indicates the complete hanger or supporting device, made according to and embodying the principles of the present invention, the same comprising a front-plate 2 and a rear-plate 3, the same being connected together by means of a connecting-strip 4 which may be formed integrally with said plates, as shown in the blank illustrated in Fig. 5 of the drawings, or said connecting-strip may be formed of a separate piece of flat metal or wire 6 and its ends secured by solder, or any other suitable fastening means, to the front-plate 25 and rear-plate, as shown in the blank illustrated in Fig. 6 of the drawings. The said front-plate 2 may be treated to produce any ornamental effect desired, both as to its outline as well as to its surface design or 30 embellishment. For example, its surface may be embossed, enameled, or otherwise treated to reproduce designs, emblems, or provide a color treatment corresponding with the color of the fabric with which it is 35 designed to be used. The said rear-plate 3 is preferably made of thin flexible metal, or other suitable material, although it is not essential that said front-plate 2 should be thin or flexible if heavier material would 40 better provide for its ornamentation. The said rear-plate 3 is provided with an opening or hatch 7, preferably centrally disposed between the ends of said rear-plate. Said rear-plate 3 is further provided with 45 pin-passages or perforations 8 and 9, one at either side of said opening or hatch 7. Said rear-plate 3 is further provided with tongues or protecting lugs 10 and 11, one adjacent to either end of said rear-plate, and 50 the same being preferably cut out of or struck up from the body of said rear-plate. Struck outwardly from the body of said rear-plate, so as to extend between the said opening or hatch 7 and the respective pin- 55 passages or perforations 8 and 9, are channeled or grooved portions 12 and 13 which provide pin guide-ways, and in like manner struck inwardly from the body of said rear-plate, so as to extend between the said 60 tongues or protecting lugs 10 and 11 and the respective pin-passages or perforations 8 and 9, are channeled or grooved portions 14 and 15 which also provide oppositely extending pin guide-ways.

The reference character 16 indicates a fastening pin, which is preferably in the form of an ordinary straight common pin provided with a head at one end and a pointed portion at the other end. The construction of the rear-plate 3 as, above indicated, permits the said fastening-pin 16 to weave through the said rear-plate, the same passing over the upper surface of the rear-plate through the channeled-portion or groove 14, then through the pin-passage or 75 perforation 8 so as to pass under the lower surface of the rear-plate through the channeled-portion or groove 12, then across the opening or hatch 7, then passing on beneath the lower surface of the rear-plate through 80 the channeled-portion or groove 13 of the rear-plate so as to pass through the pin-passage or perforation 9, and then over the upper surface of the rear-plate through the channeled-portion or groove 15.

Secured to the rear-surface of said front-plate 2 by any suitable fastening means is a bowed-portion or loop 17, the same being preferably centrally disposed between the ends of said front-plate.

In applying the said hanger or supporting device to a curtain or other drapery, the said connecting-strip 4 is doubled back upon itself so as to register together said front-plate and said back-plate. When thus formed the upper marginal edge of the curtain or draperies 18 is inserted between the said registered front-plate and rear-plate, and then the two plates are pressed together so that said bowed-portion or loop 17 forces 100 a fold 19 of the curtain or drapery 18 through the opening or hatch 7 of the said rear-plate 3. When the said front-plate and rear-plate are thus positioned the fastening pin 16 is woven into the rear-plate in the 105 manner above described so that the same passes through said fold 19 of the curtain or drapery 18 and beneath said bowed portion or loop 17 thus securing the curtain or drapery between the said front-plate and rear-plate and also holding the two plates in their clamping relation to the said curtain or drapery. When the fastening pin has been thus woven through the rear-plate 3, the said tongue or protecting lug 10 is 115 bent over the head of the fastening pin, and the tongue or protecting lug 11 is, in like manner, bent over the point of the fastening pin. In this manner the head and point of the fastening pin is protected against catching in the fabric of the curtain or drapery, and likewise against accidental removal or displacement. As will be apparent the gripping of the fabric of the curtain or drapery and the passage of the fastening pin 16 120 through the fold 19 thereof affords an exceedingly strong and secure method of grasping the curtain or drapery and also

holds or fastens upon the curtain or drapery in such a manner as to practically eliminate all danger of tearing the fabric of the curtain or drapery, yet at the same time permitting any amount of handling or movement of the curtain or drapery without danger of loosening, pulling away, or unfastening the same from said hanger or supporting device. If it should be desired either or 10 both said front-plate and said rear-plate may be provided at its periphery with one or more suitably disposed prongs or pointed lugs 20, as shown in the blank illustrated in Fig. 7 of the drawings, which may be 15 turned at right angles to the body of the plate with which they are connected together when the said plates are registered together with the curtain placed between the same the said prongs or pointed lugs 20 may be thrust 20 into the body of the fabric of the curtain or drapery and thus provide additional holding means for gripping and securing the curtain in fastening the same between the said plates. The said rear-plate 3 being 25 preferably of substantially thin flexible material the weaving of the fastening pin 16 therethrough in operative assembled relation to the said plate and curtain is easily and quickly accomplished. The said connecting-strip 4 which, as was above described, is doubled back upon itself to bring the said front and rear plates together, extends upwardly above the marginal edge of the curtain or drapery 18, and the same may 30 be bent around, as at 21, to form a supporting member or hook 22, which can be inserted through the eyelet 23 of a traveling ring 24, thereby connecting the hanger or supporting device with the curtain or drapery 40 secured thereby, to the curtain pole 25 upon which the said traveling ring runs. When desirable, however, the said doubled and upwardly extending portion of the connecting-strip 4 may be bent around into ring-form, 45 as at 26, in the manner shown in Fig. 8 of the drawings and the free end 27 of said connecting strip may be fastened to the body of said connecting-strip adjacent to its base, thus providing a traveling ring 50 directly connected with the said plates of the hanger, which may be directly suspended upon a curtain rod 28 so as to travel thereon.

Referring now to Figs. 9 to 12 inclusive of the drawings, there is illustrated therein a 55 slightly modified construction of hanger or supporting device which embodies, however, the general principles of the present device. In this form the said hanger or supporting device comprises a substantially flexible front-plate 29, of any desirable configuration, and a substantially flexible rear-plate 30, the same being connected together by 60 means of the connecting strip 31, which may be made integral with said plates, or as a separate piece suitably secured at its ends to 65 the respective plates. The said front-plate 29 is provided with a pair of suitably spaced and disposed perforations or pin-passages 32 and 33, and in like manner, the said rear-plate 30 is provided with a pair of suitably 70 spaced and disposed perforations or pin-passages 34 and 35. The said rear-plate 30 is further provided with a pair of tongues or protecting lugs 36 and 37, one adjacent to either end of said rear-plate, and the same 75 being preferably cut out of or struck up from the body of said rear-plate. The reference character 38 indicates a fastening pin, which is preferably in the form of an ordinary common pin provided with a head at 80 one end and a pointed portion at the other end. In applying the hanger or supporting device thus formed to a curtain or other drapery 39, the said connecting-strip 31 is doubled back upon itself so as to register together 85 said front-plate 29 and said rear-plate 30. When thus formed the upper marginal edge of the curtain or drapery 39 is inserted between the said registered front-plate and rear-plate, and the two plates are 90 pressed together so that the said fastening pin 38 may be woven through the two plates and the curtain or drapery held between the same in the following manner: The point of the fastening pin is inserted through the 95 perforation or pin-passage 32 so that the body of the pin passes across the outer surface of the rear-plate then through said perforation or pin-passage 32 through the body of the fabric of said curtain or drapery and 100 thus through the perforation pin-passage 34 of the front-plate across the outer surface of said front-plate so as to enter and pass through said perforation or pin-passage 35 and again through the body of the fabric of 105 said curtain or drapery so as to emerge through said perforation or pin-passage 33 of said rear-plate and thence again across the outer surface of said rear-plate. When the fastening-pin 38 has been thus woven 110 through the said plates and curtain or drapery, the said tongue or protecting-lug 36 is, in like manner, bent over the head of said fastening pin, and the tongue or protecting lug 37 is, 115 fastening-pin, thus securing the fastening pin in place and protecting the same from catching in the fabric of the curtain or drapery, and from being accidentally removed from its holding or fastening position. The metal of the plates being thin and flexible the weaving of the fastening pin through the same and the fabric of the curtain or drapery is easily accomplished. The 120 said connecting-strip 31 being doubled upon itself, may be now bent to form a hook-member 40, or any other desirable form of supporting device or suspending element.

Referring now to Fig. 13 of the drawings, there is illustrated therein a further modification of the construction of hanger or supporting-device immediately above described.

5 The only difference in this construction lies in providing channeled portions or grooves 41 and 42 between the tongue or protecting lug 36 and the perforation or pin-passage 34 and the tongue or protecting lug 37 and the 10 perforation or pin-passage 35 of the rear-plate 30, and, in the manner, providing a channeled portion or groove 43 between the perforations or pin-passages 32 and 33 of the front-plate 29, the respective channeled 15 portions or grooves providing guide-ways for the fastening-pin 38, and permitting the use of slightly heavier material in the construction of the respective front and rear plates.

20 I am aware that some changes may be made in the general arrangements and combinations of the various devices and parts, as well as in the details of the construction of the same, without departing from the scope 25 of my present invention as set forth in the foregoing specification and as defined in the appended claims. Hence, I do not limit my invention to the exact arrangements and combinations of the devices and parts as described in the said specification, nor do I confine myself to the details of the construction 30 of the said parts as illustrated in the accompanying drawings.

I claim:—

35 1. In a device of the kind described, a pair of plates adapted to be registered together with the fabric to be supported inserted therebetween, a detachable fastening pin, said rear-plate being provided with perforations 40 providing pin-passages through which said fastening-pin may be woven, and a rearwardly projecting portion provided with an opening connected with said front-plate for pressing the fabric to be supported into the 45 path of said fastening-pin so that the latter passes through said fabric and through the opening of said rearwardly projecting portion.

50 2. In a device of the kind described, a pair of plates adapted to be registered together with the fabric to be supported inserted therebetween, a detachable fastening pin, said rear-plate being provided with perforations 55 providing pin-passages through which said fastening-pin may be woven, a rearwardly projecting portion provided with an opening connected with said front-plate for pressing the fabric to be supported into the path of said fastening-pin so that the latter passes through said fabric and through the opening of said rearwardly projecting portion, and means for suspending said plates.

60 3. In a device of the kind described, a pair of plates adapted to be registered together

with the fabric to be supported inserted 65 therebetween, a detachable fastening pin, fastening pin engaging means connected with each plate so that said fastening pin may be woven through the same and through the fabric to be supported, protecting-tongues 70 connected with one of said plates and adapted to be bent over the respective ends of said fastening pin to prevent accidental displacement or removal thereof, and a suspending device mutually connected with each plate. 75

4. In a device of the kind described, a front-plate, a rear-plate, a connecting-strip interconnecting said front-plate and said rear-plate, said connecting-strip being doubled upon itself to register said front-plate 80 and said rear-plate together so that the fabric to be supported may be inserted between said front-plate and said rear-plate, a detachable fastening-pin, means connected with said front-plate and means connected with 85 said rear-plate adapted to be engaged by said fastening pin in such a manner as to permit the pin to pass through the fabric to be supported, protecting-tongues struck up from the body of said rear-plate and adapted 90 to be bent over the respective ends of said fastening pin to prevent accidental displacement or removal thereof, and the doubled over portion of said connecting-strip being bent to form a suspending-device. 95

5. In a device of the kind described, a front-plate of any ornamental configuration or character, a rear-plate, a connecting-strip interconnecting said front-plate and said rear-plate, said connecting-strip being doubled upon itself to register said front-plate 100 and said rear-plate together so that the fabric to be supported may be inserted therebetween, a detachable fastening-pin, said rear-plate being provided with perforations 105 providing pin-passages through which said fastening-pin may be woven, a rearwardly projecting portion provided with an opening connected with said front-plate for pressing the fabric to be supported into the path of 110 said fastening-pin so that the latter passes through said fabric and through the opening of said rearwardly projecting portion, and the doubled over portion of said connecting-strip being bent to form a suspending device. 115

6. In a device of the kind described, a front-plate of any ornamental configuration or character, a rear-plate, a connecting-strip interconnecting said front-plate and said rear-plate, said connecting-strip being doubled upon itself to register said front-plate 120 and said rear-plate together so that the fabric to be supported may be inserted therebetween, a detachable fastening-pin, said rear-plate being provided with perforations 125 providing pin-passages through which said fastening-pin may be woven, means connected with said front-plate for pressing the fabric

to be supported into the path of said fastening pin so that the latter passes through said fabric and engages said means, protecting-tongues struck up from the body of said 5 rear-plate and adapted to be bent over the respective ends of said fastening pin to prevent accidental displacement or removal thereof, and the doubled over portion of said connecting-strip being bent to form a suspending-device.

7. In a device of the kind described, a front-plate of any ornamental configuration or character, a rear-plate, a connecting-strip interconnecting said front-plate and said 15 rear-plate, said connecting-strip being doubled upon itself to register said front-plate and rear-plate together so that the fabric to be supported may be inserted therebetween, a detachable fastening-pin, said rear- 20 plate being provided with a centrally disposed opening or hatch, said rear-plate being further provided with a pair of perforations providing pin-passages one on either side of said opening or hatch and through 25 which said fastening-pin may be woven, a bowed-portion secured to and projecting from the rear side of said front plate, said bowed-portion registering with said opening or hatch and adapted to press a fold of 30 the fabric to be supported through said opening or hatch so as to present the same in the path of said fastening-pin so that the latter passes through said fabric and beneath said bowed-portion, and the doubled 35 over portion of said connecting-strip being bent to form a suspending-device.

8. In a device of the kind described, a front-plate of any ornamental configuration or character, a rear-plate, a connecting-strip 40 interconnecting said front-plate and said rear-plate, said connecting-strip being doubled upon itself to register said front-plate and rear-plate together so that the fabric to be supported may be inserted therebetween, a detachable fastening-pin, said rear-plate 45 being provided with a centrally disposed opening or hatch, said rear-plate being further provided with a pair of perforations providing pin-passages one on either side of said opening or hatch and through which said fastening-pin may be woven, a bowed-portion secured to and projecting from the rear-side of said front-plate, said bowed-portion registering with said opening or 50 hatch and adapted to press a fold of the fabric to be supported through said opening or hatch so as to present the same in the path of said fastening-pin so that the latter passes through said fabric and beneath said bowed-portion, protecting-tongues struck up 55 from the body of said rear-plate and adapted to be bent over the respective ends of said fastening pin to prevent accidental displacement or removal thereof, and the dou-

bled over portion of said connecting-strip 65 being bent to form a suspending-device.

9. In a device of the kind described, a front-plate of any ornamental configuration or character, a rear-plate, a connecting-strip interconnecting said front-plate and said 70 rear-plate, said connecting-strip being doubled upon itself to register said front-plate and rear-plate together so that the fabric to be supported may be inserted therebetween, a detachable fastening-pin, said rear- 75 plate being provided with a centrally disposed opening or hatch, said rear-plate being further provided with a pair of perforations providing pin-passages one on either side of said opening or hatch and through 80 which said fastening-pin may be woven, outwardly pressed channeled portions providing fastening pin guide ways formed in said rear-plate so as to extend between said pin-passages and said opening or hatch, in- 85 wardly pressed channeled portions providing fastening pin guide-ways formed in said rear-plate so as to extend from said pin-passages toward the ends of said rear-plate, a bowed-portion secured to and projecting 90 from the rear side of said front-plate, said bowed-portion registering with said opening or hatch and adapted to press a fold of the fabric to be supported through said opening or hatch so as to present the same 95 in the path of said fastening-pin so that the latter passes through said fabric and beneath said bowed-portion, and the doubled over portion of said connecting-strip being bent to form a suspending-device.

10. In a device of the kind described, a front-plate of any ornamental configuration or character, a rear-plate, a connecting-strip interconnecting said front-plate and said 100 rear-plate, said connecting-strip being doubled upon itself to register said front-plate and rear-plate together so that the fabric to be supported may be inserted therebetween, a detachable fastening-pin, said rear-plate 105 being provided with a centrally disposed opening or hatch, said rear-plate being further provided with a pair of perforations providing pin-passages one on either side of said opening or hatch and through which said fastening-pin may be woven, outwardly 110 pressed channeled portions providing fastening pin-guide-ways formed in said rear-plate so as to extend between said pin-passages and said opening or hatch, inwardly 115 pressed channeled portions providing fastening pin guide-ways formed in said rear-plate so as to extend from said pin-passages toward the ends of said rear-plate, a bowed-portion secured to and projecting from the rear side of said front-plate, said bowed- 120 portion registering with said opening or hatch and adapted to press a fold of the fabric to be supported through said open-

ing or hatch so as to present the same in the path of said fastening-pin so that the latter passes through said fabric and beneath said bowed-portion, protecting-
5 tongues struck up from the body of said rear-plate and adapted to be bent over the respective ends of said fastening pin to prevent accidental displacement or removal thereof, and the doubled over portion of said

connecting-strip being bent to form a sus- 10 pending-device.

In testimony, that I claim the invention set forth above I have hereunto set my hand this thirtieth day of August, 1913.

RUSSELL WHITCOMB.
